UNITED STATES PATENT OFFICE.

CHARLES ALGERNON PARSONS, ALFRED QUINTIN CARNEGIE, AND MATTHEW BONE, OF NEWCASTLE-UPON-TYNE, AND STANLEY SMITH COOK, OF WALLSEND-UPON-TYNE, ENGLAND; SAID CARNEGIE, SAID BONE, AND SAID COOK ASSIGNORS TO SAID PARSONS.

MANUFACTURE OF BLADING FOR TURBINES.

Application filed April 14, 1920, Serial No. 373,937. Renewed August 22, 1922. Serial No. 583,643.

To all whom it may concern:

Be it known that we, THE HONOURABLE SIR CHARLES ALGERNON PARSONS, K. C. B., ALFRED QUINTIN CARNEGIE, and MATTHEW BONE, all subjects of the King of Great Britain, and residents of Heaton Works, Newcastle-upon-Tyne, in the county of Northumberland, England, and STANLEY SMITH Cook, a subject of the King of Great Britain, and resident of Turbinia Works, Wallsend-upon-Tyne, in the county of Northumberland, England, have invented certain new and useful Improvements in the Manufacture of Blading for Turbines, of which the following is a specification.

The present invention relates to turbine blading and has for its object an improved manner of manufacture whereby the blade proper combined integrally with its base may be readily and cheaply produced.

In the specification of British application No. 16910 of 1918, we have described a method of manufacturing turbine blading in which the base of the blade or a mass of metal from which the base may be subsequently machined is shaped in a die having a suitable aperture, the blade proper being formed by extrusion through an orifice in the die.

In carrying out this method of manufacture difficulty has been experienced owing to the fact that with small billets there is a tendency for the edges of the blade, and especially the finer edge, to be extruded in a jagged condition.

We have found that this objection may be overcome by so shaping the aperture in the die that when the billet of metal is placed therein, it does not completely fill the aperture in proximity to the orifice through which the blade is extruded.

The invention, therefore, consists in forming a turbine blading element from a billet in a die, having an aperture in which the base of the blade or a mass of metal from which the base can be subsequently machined is shaped and an orifice through which the blade proper is extruded, in such a manner that when the operation is carried out an air space is left in proximity to the lower part of the billet near the edge of the orifice.

The invention further consists in forming

a die of the type and for the purpose indicated, having in the aperture which receives the billet of metal a recess in close proximity to the extrusion orifice.

The invention also consists in a die of the type and for the purpose indicated, provided in close proximity to the extrusion orifice with a recess wholly or partially surrounding the orifice, of such shape that when the billet is inserted an air space is left in the neighbourhood of the lower part of the billet near the edge of the orifice.

The invention moreover consists in so reducing the section of the billet in proximity to the orifice that an air space is left in the neighbourhood of the lower part of the billet near the edge of the orifice.

The invention further consists in the improved means for manufacturing turbine blades hereinafter described.

In the accompanying drawings:

Figures 1 and 2 are sections taken at right angles to each other, and

Figure 3 is a plan of one form of die made in accordance with the invention.

Figures 4 and 5 illustrate modifications.

In carrying the invention into effect, we employ a die similar to that described in the specification of the above-mentioned application, that is to say, a die having an aperture 1 in which the billet of metal 2 may be placed and provided with an orifice 3 through which the blade is extruded. Instead, however, of forming the sides of the aperture parallel throughout their length or converging towards the orifice at the bottom of the aperture, we form some or all of the sides of this aperture so that they diverge as the bottom of the aperture is approached, thus making the cross section of the aperture constant throughout a portion of its length but increased near the bottom.

By suitably shaping the recess thus formed in the aperture, the parallel-sided billet will not completely fill the increased volume of the aperture but will leave an air space therein, and we have found that by this means an even and continuous, instead of a jagged edge is produced on the extruded blade.

In the form of the invention illustrated in Figures 1-3, all the sides of the aperture are made to diverge toward the orifice at

the bottom of the aperture, thus leaving a recess 4 completely surrounding the billet 2.

As pointed out above the greatest tendency to unevenness is found on the finer edge of the blade, and we may therefore merely form a recess in the side of the aperture adjacent to the end of the orifice through which the finer edge is extruded. 10 Preferably, however, a recess is formed also on the opposite side of the aperture, that is to say, adjacent to both ends of the orifice. This arrangement is illustrated in Figure 4.

We do not confine ourselves to any particular shape of recess, this being a matter which must be determined by experiment in individual cases. For example, we may find it advisable so to shape the recess that its walls converge in a direction away from 15 the orifice and merge gradually into the parallel-sided part of the aperture. Or again, it may be advantageous to make the walls of the recess parallel leaving a shoulder between them and the parallel-sided 20 part of the aperture in which the billet fits more or less closely before operation of the ram. This latter arrangement is shown in 25 Figure 5, in which the recess 4, being of the same section throughout its length, is not 30 cut so deeply into the die as in the previous examples.

In a further modification, the sides of the aperture in the die are formed parallel throughout their length and the recess or 35 air space is formed by removing metal from the lower part of the billet so that the sides of the billet are parallel throughout a portion of its length, but some or all of the sides converge towards the bottom.

40 The metal of the billet when under the heavy pressure necessary to effect extrusion will enter the recess to more or less degree, but the entrapped air will serve as an insulator against the loss of heat so that the

portion of the billet which goes to make up 45 the free edge of the blade will be maintained at a high temperature to get the result desired.

Claims:

1. A die of the type described having an 50 aperture to receive the billet provided with an enlarged bottom, and an orifice through which the billet may be extruded extending from said enlarged bottom.

2. A die of the type described having an 55 aperture to receive the billet, an orifice through which the billet may be extruded, and a recess in the aperture, in proximity to the extrusion orifice.

3. A die of the type and for the purpose indicated, provided in close proximity to the extrusion orifice with a recess wholly or partially surrounding the orifice, of such a shape that when the billet is inserted, an air space is left in the neighbourhood of 60 the lower part of the billet near the edge of the orifice.

4. In a method of extruding turbine blading, the step of reducing the section of 70 the billet in proximity to the extrusion orifice so that an air space is left in the neighbourhood of the lower part of the billet near the edge of the extrusion orifice.

5. A drop forging die provided with an 75 extrusion orifice and a recess in proximity thereto, substantially as described.

6. The herein described method of extruding turbine blades, which consists in associating a billet and a die so as to provide a space between billet and die in proximity to the extrusion orifice, and applying pressure to the billet.

In testimony whereof we have signed our names to this specification.

CHARLES ALGERNON PARSONS.

ALFRED QUINTIN CARNEGIE.

MATTHEW BONE.

STANLEY SMITH COOK.
